Primary Examiner — Cynthia M. Chin

(57) **CLAIM**

The ornamental design for a toy building brick, as shown and described.

DESCRIPTION

FIG. 1 is a top isometric view of a toy building brick showing my new design, a bottom isometric view being a mirror image thereof;

FIG. 2 is a right side view of the toy building brick, a left side view, a rear view and front view being mirror images thereof;

FIG. 3 is a bottom view of the toy building brick; and, FIG. 4 is a cross-sectional view of the toy building brick taken along line 4-4 of FIG. 2 to illustrate an opening extending through toy building brick.
